C. W. DALBERG,
COMBINED FLASH LIGHT AND MIRROR,
APPLICATION FILED JUNE 10, 1918.

1,304,856.

Patented May 27, 1919.

UNITED STATES PATENT OFFICE.

CARL WILLIAM DALBERG, OF DEARY, IDAHO.

COMBINED FLASH-LIGHT AND MIRROR.

1,304,856.

Specification of Letters Patent. Patented May 27, 1919.

Application filed June 10, 1918. Serial No. 239,267.

To all whom it may concern:

Be it known that I, CARL W.M. DALBERG, a citizen of the United States, residing at Deary, in the county of Latah, State of Idaho, have invented certain new and useful Improvements in Combined Flash-Lights and Mirrors; and I do hereby declare the following to be a full, clear, and exact description of the invention, such as will enable others skilled in the art to which it appertains to make and use the same.

The invention relates to an electric pocket flashlight and more particularly to the class of combined flashlights and mirrors.

15 The primary object of the invention is the provision of a flashlight of this character wherein the construction thereof permits the use of the same in the ordinary well known manner for the illumination of the electric bulb for lighting purposes, and the lid or cover on the casing of said flashlight can be open and carries a mirror so that the same will be useful and the electric bulb when illuminated will enable the mirror to be used 25 in the dark should the occasion require.

Another object of the invention is the provision of a flashlight of this character wherein the construction thereof is novel in form, the casing being designed to support not 30 only the battery for the electric bulb, but a mirror, and also forms a pocket for a comb, thus the flashlight serving for illuminating purposes, a mirror and a comb carrier, thereby rendering the same useful for illuminating and toilet purposes.

40 A further object of the invention is the provision of a flashlight of this character which is comparatively simple in construction, neat and attractive in appearance, useful for the purposes named, and inexpensive to manufacture.

With this and other objects in view the invention consists in the features of construction, combination and arrangement of parts 45 as will be hereinafter fully described, illustrated in the accompanying drawing, and pointed out in the claims hereunto appended.

In the accompanying drawing:

Figure 1 is a side elevation of a flashlight 50 constructed in accordance with the invention;

Fig. 2 is a top plan view thereof;

Fig. 3 is a plan view showing the casing in open position;

55 Fig. 4 is a vertical longitudinal sectional view;

Fig. 5 is a vertical transverse sectional view;

Fig. 6 is an end edge elevation showing the cover or lid section of the casing open. 60

Similar reference characters indicate corresponding parts throughout the several views in the drawing.

Referring to the drawing in detail, A designates generally the main body section 65 and B the swinging lid or cover section of the casing of the flashlight, the details of which will be hereinafter fully described. The main body section A comprises a back wall 10, side walls 11 and an end wall 12 respectively, thus the opposite end being open and also the front or top of the body section and within the latter is adapted to be received a dry cell battery 13 of the ordinary well known construction having the resilient poles or contacts 14 and 15 respectively. The battery is removably fitted within the body section and the pole or contact 14 engages with an electric bulb 16 of the usual construction which is detachably screwed 70 into a socket 17 formed on an ear 18 at right angles to the back wall of the body section and integral with a hinge 19 fixed to the back wall 10 at the open end of the body section and swingingly connecting the cover or lid section B thereto. Mounted on one side wall 11 of the body section next to the contact 15 is a resilient switch 20 which is adapted to close the circuit between the battery 13 and the bulb 16 for illuminating the latter, 75 the switch 20 being normally open and is manually operated.

The lid or cover section B closes the open end and front or top of the body section A and has formed in its end closing wall an 80 opening 21 for the electric bulb 16 to permit the projecting of the light from the casing of the flashlight when said casing is closed in the usual manner. Mounted interiorly of the cover or lid section B is a mirror frame 85 22 for retaining a mirror 23 which on the opening of the lid or cover section B can be used in the usual manner and on the closing of the switch 20 the bulb 16 will be illuminated to light the mirror for the use thereof 90 100 105 in the dark.

Formed in the lid or cover section B at the back of the mirror 23 is a pocket 24 for receiving a comb 25 which is readily removable therefrom for use by the operator 110 of the flashlight, the pocket 24 being extended through the free end of the lid or

cover section B, which end is formed with a notch 26 to permit easy access to the comb 25 for its removal therefrom.

The side flange edges 27 of the lid or 5 cover section B are formed with indentations providing latch lugs 28 for frictionally engaging in holes or apertures 29 provided in the side walls 10 of the body section of the casing so as to retain the lid or 10 cover section closed.

The hinge 19 at opposite ends thereof is formed with wings 30 serving as guards for the battery 13. The end wall 12 of the 15 body section closes the open end of the pocket 24 when the lid is closed upon the body section of the casing, as will be apparent.

From the foregoing it is thought that the 20 construction and manner of use of the flashlight will be clearly understood, and therefore a more extended explanation has been omitted.

What is claimed is:

1. In a flashlight of the character described, a casing having an initially open 25 end and side, a swinging lid adapted to close said end and side of the casing, a mirror mounted on the inside of the lid, and an electrically lighted bulb carried in the casing 30 and exposed through the lid and positioned to illuminate the mirror when the lid is in open position.

2. In a flashlight of the character described, a casing having an initially open end and side, a swinging lid adapted to 35 close said end and side of the casing, a mirror mounted on the inside of the lid, an electrically lighted bulb carried in the casing and exposed through the lid when in closed position and positioned to illuminate 40 the mirror when the lid is in open position, and means supported by the casing for controlling the lighting of the flashlight.

3. In a flashlight of the character described, a casing having an initially open 45 end and side, a swinging lid adapted to close said end and side of the casing, a mirror mounted on the inside of the lid, an electrically lighted bulb carried in the casing and exposed through the lid when in closed 50 position and positioned to illuminate the mirror when the lid is in open position, and means supported by the casing for controlling the lighting of the flashlight lid, the light being formed with a pocket adapted to receive a comb accessible through one end of said lid.

In testimony whereof, I affix my signature in the presence of two witnesses.

CARL WILLIAM DALBERG.
